C. E. BUNKER

UMBRELLA RIB AND STRETCHER AND ATTACHING MEANS THEREFOR

Filed May 17, 1922

Fig. 8.

By *Watson E. Coleman*
Attorney

Inventor:

John H. Bunker
Carey E. Bunker,

UNITED STATES PATENT OFFICE.

CAREY E. BUNKER, OF OREGON, MISSOURI.

UMBRELLA RIB AND STRETCHER AND ATTACHING MEANS THEREFOR.

Application filed May 17, 1922. Serial No. 561,647.

To all whom it may concern:

Be it known that I, CAREY E. BUNKER, a citizen of the United States, residing at Oregon, in the county of Holt and State of Missouri, have invented certain new and useful Improvements in Umbrella Ribs and Stretchers and Attaching Means Therefor, of which the following is a specification, reference being had to the accompanying drawings.

It is the purpose of the present invention to provide an article of this kind including attaching means for detachably connecting a rib to the wire bearing of the collar at the top of the umbrella stick, or for connecting the stretcher to a wire bearing of a collar on the runner, whereby the rib or stretcher may be attached to these respective parts, without removing the wire bearing or cutting the same.

Another purpose is to provide attaching means for a rib or stretcher, whereby the stretcher or rib may be connected to the wire bearing without removing the wire, and after the stretcher or rib is connected it cannot be detached without first springing the catch or removing the wire bearing.

A still further purpose is to provide attaching means for a stretcher or rib, so that the rib or stay may be attached or detached to the wire bearing, without breaking the catch and without removing the wire bearing.

A still further purpose is the provision of attaching means for a stretcher or rib comprising a rib body, which is U-shaped in cross section for the reception of a shank of a spring, which has an arm overlying the wire bearing engaging notch of the head of the stay or rib, to retain the wire bearing in the notch, either so it can be detached, or cannot be detached, without removing the wire bearing, or without breaking the spring catch.

Furthermore the invention has for its purpose the provision of means caused to be formed in the sides of the U-shaped body of the stretcher or rib, for the purpose of retaining the shank of the spring catch in engagement or connected to the body of the rib or stretcher.

It is to be understood that the particulars herein given are in no way limitative and that while still keeping within the scope of the invention, any desired modifications of

detail and desired proportions may be made in the apparatus according to circumstances.

The invention comprises further features and combination of parts, as will be herein-after set forth, shown in the drawings and claimed.

In the drawings:

Figure 1 is a view in side elevation of a portion of a rib or stretcher of the umbrella, showing the improved attaching means applied;

Figure 2 is a perspective view of the end of a stretcher or rib, showing a construction similar to that shown in Figure 1;

Figure 3 is a detail perspective view of the spring;

Figure 4 is a view in side elevation of an end portion of a stretcher or rib, showing a modified construction of attaching means, wherein the rib or stretcher may be disconnected from its wire bearing, without removing the wire bearing, and without breaking the catch or spring.

Figure 5 is a cross sectional view on line 5-5 of Figure 2, showing the manner of attaching the spring to the body of the stretcher or rib;

Figure 6 is a view in side elevation showing a modified form of attaching means for the rib or stretcher, wherein an overlying hook is stationary or fixed relatively to the body of the stretcher or rib, to retain the rib or stretcher securely attached to its wire bearing, and also showing a modified arrangement of the spring;

Figure 7 is a cross sectional view of the character shown in Figure 5, showing the shank of the rib or stretcher rectangular in cross section;

Figure 8 is a detail perspective view of the spring, showing a modified construction, wherein the grooves 12 in Figure 3 are eliminated, and in their stead notches are substituted.

Referring to the drawings, 1 designates the body of a stretcher or rib, which is of the usual construction, in so far as its cross sectional shape is concerned. In other words the body of the stretcher is U-shaped in cross section, therefore the body of the stretcher or rib has a channel substantially its full length. However, the channel is closed, at a point adjacent the end of the stay or rib, by pressing the sides of the U-shaped stretcher or rib in contact with each other,

or otherwise arranging or constructing the sides to attain the result as at 2.

The end of the rib or stretcher is enlarged, as shown at 3, and the end of the enlargement, especially in Figures 1, 2 and 4 is provided with a wire bearing engaging cavity or recess 4. In other words this cavity or recess 4 receives the wire bearing, which is mounted in the usual groove (not shown) of the collar on the top of the umbrella stick, or receives the wire bearing of the collar which is carried by the runner (not shown) of the umbrella stick. In fact in the construction of umbrellas, the ribs and the stretchers are connected to collars, the upper one being carried by the umbrella stick, the lower one is usually carried by the runner, used for opening the umbrella.

A spring catch 5 is arranged adjacent one edge 6 of the enlargement 3, and has a shank 7, which is offset from the portion 8 of the spring catch, due to the formation of the curved portions 9, at a point where the shank connects with the spring catch. The portion 8 of the spring catch when in its holding position lies flat against the edge 6 of the body 3 of the stretcher or rib, whereas the shank 7 engages the channel of the stretcher or rib. The junction where the spaced sides of the U-shaped body of the stretcher or rib merge into the pressed together portions of the sides of the stretcher, conform to the curvatures 9, which connect the spring catch and its shank 7, so as to reinforce the spring catch, and to assist in holding the shank in its position against movement toward the end of the stretcher in which the cavity or recess 4 is formed. The opposite sides of the U-shaped stretcher or rib are swaged toward each other, thereby causing to be formed projections 11 engaging each other, and overlying the shank of the spring catch. In fact the shank 7 of the spring catch is provided with arcuate shaped grooves or recesses 12, which are engaged by the overlying projections or protuberances 11, thereby not only acting to lock the catch of the spring catch in the U-shaped body of the stretcher or rib, but also acting to prevent longitudinal movement of the shank. The portion 8 of the spring catch is capable of being sprung laterally, to permit the wire bearing to enter the cavity or recess 4. In fact the terminal of the portion 8 of the spring catch is curved, as shown at 13^a, and this curved portion overlies the foreshortened side wall of the cavity or recess, acting to materially retain the wire bearing in the cavity or recess. The terminal or extremity of the curved portion 13 contacts with the overlying wall or arm 14, which adjoins the cavity or recess 4. The adjacent ends of the arm or wall 14 and the curved portion of the spring catch are provided with beveled faces 15, so that by en-

gaging the wire bearing between these inclined faces, and applying sufficient pressure to the rib or stretcher, the curved portion 13^a and the arm 14 will separate. In fact the curved portion 13^a will spring laterally, to permit the wire to enter. Since the curved portion 13^a in Figures 1 and 2 is more abrupt, than the curvature of the curved portion 13 in Figure 4, it will act to overlie the wire bearing, and retain the rib or stretcher as connected thereto. In other words by this construction of the abrupt curvature of the portion 13^a of the spring catch, it is possible to pull upon the stretcher or rib, and it will not disconnect from the wire bearing of the collar at the upper end of the umbrella stick, or the collar on the runner. For instance the pull can be in a direction longitudinally of the stretcher or rib, and since the curved portions 9 (which are located adjacent the shank) abut where the opposite walls of the stretcher merge together, the spring catch will not yield, and permit the wire to be removed or disengaged from the cavity or recess 4.

However the curvature of the portion 13 of the spring catch in Figure 4 is more gradual, so is the corresponding edge or face of the overlying arm or wall of the recess or cavity 4, so that by any pull on the stretcher in a direction longitudinally of the stretcher or rib, the wire bearing will cause the portion 13 to separate and permit the stretcher or rib to become detached.

The curved portion 13^a of the spring catch (in Figure 1) has its extremity 16 partly underlying the extremity of the arm or wall 14, in order to insure the prevention of the stretcher or rib becoming detached from the wire bearing.

In Figure 6 the extraordinarily long curved portion, similar to the curved portions 13 or 13^a of the spring catch 5, in Figures 1 to 4 inclusive, is eliminated, and the arm or wall 14^a of the enlargement 3 is extraordinarily long, and its end face 17 is beveled, with which the extremity 18 of the spring catch 5 engages. The extremity of the spring catch 5 in Figure 6 is beveled as at 19, in order to permit the wire bearing to engage between the beveled surfaces 17 and 19 in order to cause the spring catch 5 to separate from the enlargement 3, and permit the wire bearing to enter the cavity or recess 4.

In detaching the stretcher or rib in Figures 1, 2 and 6, it is necessary to use a suitable tool to spring the catch in a lateral direction, in order to permit the wire to leave the cavity or recess.

The invention having been set forth, what is claimed is:—

1. In an attaching device for umbrella ribs, a body having an enlargement at one end provided with a recess for the reception

of a wire bearing of an umbrella, a spring catch connected to the body and overlying one edge of said enlargement and provided with an extension overlying the recess, the adjacent ends of the extension and the overlying wall of the recess being provided with beveled faces to permit the wire bearing to enter the recess.

2. In a device for the purpose indicated, comprising a U-shaped umbrella rib, one end of the rib being provided with a spring closed opening adapted for the reception of a wire bearing of an umbrella, said spring closed opening including a movable member

to be engaged by the wire bearing, to permit 15 the wire bearing to enter said spring closed opening.

3. Umbrella rib attaching means comprising a rib substantially U-shaped in cross section, the end portion of said rib being enlarged and provided with a recess, and a resilient member disposed in the channel of the U-shaped rib and coacting with the recess of the rib to provide an opening.

In testimony whereof I hereunto affix my 25 signature.

CAREY E. BUNKER.
